UNITED STATES PATENT OFFICE.

CHARLES G. PERKINS, OF HARTFORD, CONNECTICUT, ASSIGNOR TO THE PERKINS ELECTRIC SWITCH MANUFACTURING COMPANY, OF SAME PLACE.

FLUSH-SWITCH SUPPORT.

SPECIFICATION forming part of Letters Patent No. 663,039, dated December 4, 1900.

Application filed June 28, 1900. Serial No. 21,961. (No model.)

To all whom it may concern:

Be it known that I, CHARLES G. PERKINS, a citizen of the United States, residing at Hartford, in the county of Hartford and State of Connecticut, have invented certain new and useful Improvements in Flush-Switch Supports, of which the following is a specification.

This invention relates to the means employed for supporting flush electrical snap-switches either singly or in gangs.

The object of the invention is to simplify the method of and to reduce the cost of the means for supporting flush switches.

The invention resides in a frame or box so constructed and a switch receptacle or receptacles so shaped that after the frame or box has been fixed in position in the wall of the building the receptacle or receptacles containing the switch mechanisms may be conveniently located and firmly secured in place without the employment of the holding-plate now commonly used.

The invention is illustrated in the accompanying drawings in connection with a frame designed for a gang of three flush rotary snap-switches.

Figure 1 is a plan view showing a portion of the cover-plate, the frame, and one of the receptacles without the switch mechanisms. Fig. 2 is a transverse section taken through the frame and the empty receptacle. Fig. 3 is a plan of the frame. Fig. 4 is an edge view of the frame with a portion broken away. Fig. 5 is a side view of the receptacle, and Fig. 6 is a bottom view of the receptacle.

The frame 1, which is that part designed to be permanently set in a wall of the building, may be cast to shape or may be bent or stamped from sheet metal. This part may be arranged for one, two, three, or more switches. The sides may be of any suitable width and the bottom may be open or closed, as desired.

From the sides 2, near each end 3, of the oblong frame for three switches that is shown there project wings 4, which are perforated for the passage of the screws employed to hold the frame in position in the wall, and extending inwardly from the opposite sides of

the frame are lugs 5, that are drilled and

tapped for receiving the screws which retain the switch-receptacles. The outer faces of these lugs are a little below the outer edge of the frame and those opposite each other form a pair for each receptacle.

55

The receptacle shown is a circular porcelain cup 6, having insulated passages 7 for the circuit-wires that are to be connected with the switch mechanisms placed in the receptacle. In diametrically opposite sides of the 60 walls of this receptacle and extending from the bottom nearly to the top are recesses 8. These recesses are shaped to receive the opposite lugs that extend inwardly from the side walls of the frame, and they extend as 65 near to the top of the receptacle as the distance that the outer faces of the lugs are below the outer edge of the frame, so that the edge of the frame and the edge of the receptacle will be substantially flush. Perforations 9 are made from the top downwardly to the recesses through the sections 10 of the receptacle-walls that are above the recesses. The receptacle, with the switch mechanism, is put into the frame with the lugs extending 70 into the recesses, and then screws 11 are passed through the perforations 9 into the tapped perforations in the lugs for holding the receptacle on the lugs in the frame. After the building-wall has been finished, as 75 by plastering, around one of these frames the receptacles are placed in position on the lugs and secured by the screws passed through the receptacles into the lugs. With this construction it is easy to place receptacles containing the switch mechanisms in place or to remove them from place.

It is not necessary to employ a holding-plate for supporting the receptacles, nor is it necessary to employ independent ears for attaching the receptacles to the frame or to a holding-plate. The design of the frame is simple, and the shape of the receptacle is such that it can be cheaply manufactured. There is no danger of breaking or damaging 95 one of these frames when the wall is being finished about it, and it is not possible to wrongly set one of the receptacles in the frame.

After the receptacles have been placed in 100

the frame an ornamental cover-plate 12 is placed over the frame and held in place by the handles 13 in the usual manner.

I claim as my invention—

5 1. The combination of a metallic frame having lugs projecting inwardly therefrom with the outer faces of the lugs in a plane below the outer edge of the frame and an insulating-receptacle having recesses that open 10 from the back edge of the receptacle and that are adapted to receive the lugs, substantially as specified.

2. The combination of a metallic frame having lugs projecting inwardly therefrom 15 with the outer faces of the lugs in a plane below the outer edge of the frame, an insulating-receptacle having recesses that open from the back edge of the receptacle and that are

adapted to receive the lugs, and screws passing through perforations in the receptacle-walls into the lugs, substantially as specified. 20

3. The combination of a metallic frame having wings projecting outwardly therefrom and lugs extending inwardly therefrom, with the outer faces of the lugs in a plane below 25 the outer edge of the frame, an insulating-receptacle having recesses that open from the back edge of the receptacle and that are adapted to receive the lugs, and screws passing through perforations in the receptacle-walls into the lugs, substantially as specified. 30

CHARLES G. PERKINS.
